L. F. MORTIMER

DIAL LOCK FOR AUTOMATIC TELEPHONES

Filed Dec. 31, 1925

FIG. 2.

FIG. 1.

FIG. 4.

FIG. 6.

FIG. 8.

INVENTOR,
Lewis F. Mortimer,
By Martin O. Smit, Atty.

UNITED STATES PATENT OFFICE.

LEWIS F. MORTIMER, OF LOS ANGELES, CALIFORNIA.

DIAL LOCK FOR AUTOMATIC TELEPHONES.

Application filed December 31, 1925. Serial No. 78,532.

My invention relates generally to telephones and more particularly to dial locks for automatic telephones, the principal object of my invention being to provide relatively simple and convenient means for securely locking the rotary dial plate of an automatic telephone and consequently preventing the unauthorized use of the telephones for outgoing calls.

10 Further objects of my invention are to provide a dial lock of the character referred to that is relatively simple in construction, capable of being easily and cheaply produced, and which will be very effective in 15 performing its intended functions.

It will be understood that in practically all large telephone exchanges now in operation, the majority of the telephones are leased or supplied to the subscribers on a 20 metered service plan, that is, a fixed charge for each outgoing call. Where such service is in vogue, it is difficult for the subscriber to prevent the unauthorized use of his telephone, and it is the purpose of my invention 25 to provide relatively simple dial locking means that may be easily and quickly applied to or removed from the calling dial portion of an automatic telephone and which will be effective in preventing anyone except the subscriber or holder of the key of the locking device from actuating the dial to make a call.

With the foregoing and other objects in view, my invention consists in certain novel 35 features of construction and arrangement of parts that will be hereinafter more fully described and claimed and illustrated in the accompanying drawings in which:

Fig. 1 is a perspective view of a dial locking plate of my improved construction.

Fig. 2 is a top plan view of the base portion of an automatic telephone and showing my improved locking device in position on the rotary calling dial.

Fig. 3 is a side elevational view of the base portion of an automatic telephone and showing the locking plate in position on the dial thereof.

Figs. 4 and 5 are respectively top plan and 50 side elevational views of a modified form of the dial locking device.

Fig. 6 is a top plan view of a further modified form of the dial lock.

Fig. 7 is an enlarged cross section taken on the line 7-7 of Fig. 6.

Fig. 8 is a top plan view of a further modified form of the dial lock.

Fig. 9 is an enlarged cross section taken approximately on the line 9-9 of Fig. 8.

Referring by numerals to the accompanying drawings which illustrate a practical embodiment of my invention, and particularly to the form of device illustrated in Figs. 1, 2, and 3, 10 designates the base portion of a desk telephone instrument of the automatic dial calling type, 11 the post or standard that supports the transmitter and receiver and 12 the circular base upon which is mounted for rotation the dial 13 having the finger tip openings 14.

Secured in the usual manner by screws 15 to the side of the circular base 12 is an upwardly and inwardly projecting hook 16, the upper portion of which overlies the perforated marginal portion of the dial 13 and serving as a stop for the finger while the dial plate is being rotated in making a call.

The locking means contemplated by my invention comprises an arcuate plate 17 that is adapted to overlie a portion of dial 13, and formed in said plate near one end thereof is an aperture 18 that is adapted to coincide with one of the apertures 14 in the dial. A portion of the material forming plate 17 is pressed upwardly at the inner end of the 85 perforations 18 to provide a horizontally disposed lip or finger 19, which, when the device is applied for use, overlies hook or finger stop 16.

Formed integral with the outer edge of 90 arcuate plate 17 and depending therefrom is a curved plate 20 that is adapted to overlie a portion of the edge of the circular base 12 and particularly that portion to which the base of hook 16 is secured.

When the latching plate constructed as just described is applied to the dial, the hook or finger 19 occupies a position over the hook 16 and depending plate 20 overlies the base portion of said hook 16 as illustrated in Figs. 2 and 3. The locking plate is locked to the perforated dial by the shackle portion of a small padlock P, and which shackle portion passes through aperture 18 and one of the apertures 14 in said dial. With the plate locked to the dial as

just described, it will be impossible to rotate the dial to the proper successive positions to complete the call, inasmuch as a substantial portion of the plate 17 is positioned in front of the stop hook 16 and as plate 20 covers the base portion of the hook 16, it will be impossible for the screws 15 that secure the hook 16 to base 12 to be removed, in which latter event it might be possible to 10 rotate the perforated dial with the locking plate screwed thereto into the positions necessary to make a call.

Obviously the subscriber of the telephone or some authorized person holds the key or 15 keys to the padlock and when the latter is unlocked and the shackle disengaged from the dial and perforation 18, the locking plate may be very easily and quickly removed so as to permit the dial to be used in the ordinary manner.

In the modified form of locking device illustrated in Fig. 4 and 5, a straight bar 21, preferably of metal, has one end bent downwardly so as to engage through one of the 25 perforations in the dial when bar 21 is arranged diametrically on top of said dial and the opposite end of bar 21 is bent downward to form an L-shaped member 22, the vertical leg of which is adapted to overlie the 30 vertical portion of stop hook 16.

Depending from bar 21 is a pin 23 that is adapted to pass through one of the apertures in the dial and when the locking bar is properly arranged for use, the shackle of 35 a padlock passes around the vertical leg of the L-shaped member and the adjacent vertical leg of the stop hook 16.

In the modified construction illustrated in Figs. 6 and 7, a top plate 24 is provided 40 adjacent to one end with a perforation 25 and depending from the other end of said plate is a stud 26 from the lower portion of which projects outwardly a narrow plate 27 that lies parallel with plate 24 and said 45 plate 27 being provided with a perforation 28 that is in vertical alignment with perforation 25. When this locking device is applied for use plate 27 and stud 26 are inserted through one of the perforations in 50 the dial and the shackle of a padlock passes through the aligned perforations 25 and 28. When thus locked to the dial, it functions as a stud to engage fingers 16 thereby limiting 55 the rotary motion that may be imparted to the calling dial.

In the modified construction illustrated in Figs. 8 and 9, a base plate 29 has secured 60 thereto a pair of pins 30 that extend upwardly through apertures formed in an upper plate 31 and said pins pass into the body of a padlock 32 which latter is secured to said top plate 31. As a result of this arrangement, the plates 29 and 31 may move 65 away from each other when the padlock is unlocked and into position adjacent to each

other when said padlock is locked. Depending from the underside of top plate 31 is a lug or stud 33 that is adapted to engage through one of the apertures in the dial.

When this form of lock is applied to the dial plate, the rotary movement of the latter toward the hook 16 is limited.

Thus it will be seen that I have provided relatively simple, practical and effective means for locking the dial plate of an automatic telephone and consequently preventing the unauthorized use of said telephone.

It will be understood that minor changes in the size, form and construction of the various parts of my improved lock may be made and substituted for those herein shown and described without departing from the spirit of my invention, the scope of which is set forth in the appended claims.

I claim as my invention:

1. The combination with an automatic telephone, its rotary dial and finger stop hook, of a plate that is curved lengthwise and is substantially L-shape in cross section so that it will overlie a portion of the top and edge of the rotary dial of the telephone and which plate is provided with an aperture that is adapted to coincide with one of the apertures in the dial and receive a detachable locking device.

2. The combination with an automatic telephone, its rotary dial and finger stop hook, of a plate adapted to overlie a portion of the rotary dial, which plate being provided with an aperture that is adapted to coincide with one of the apertures in the dial and receive a detachable locking device and a finger carried by said plate, which finger is adapted to overlie the finger stop hook.

3. The combination with an automatic telephone, its rotary dial and finger stop hook, of a plate adapted to overlie a portion of the rotary dial, which plate is provided with an aperture that is adapted to coincide with one of the apertures in the dial and receive a detachable locking device and a plate depending from the outer edge of the first-mentioned plate and adapted when the device is applied for use to overlie the base portion of the finger stop hook.

4. The combination with an automatic telephone, its rotary dial and finger stop hook, of a plate adapted to overlie a portion of the rotary dial, which plate is provided with an aperture that is adapted to coincide with one of the apertures in the dial and receive a detachable locking device, a finger carried by said plate, which finger is adapted to overlie the finger stop hook and a plate depending from the outer edge of the first-mentioned plate and adapted when the device is applied for use to overlie the base portion of the finger stop hook.

5. A dial lock for automatic telephones comprising a plate provided adjacent to one

end with an aperture, a finger projecting from said plate at one end of said aperture and a plate projecting from one edge of the first mentioned plate and arranged substantially at right angles thereto.

6. In a dial lock for automatic telephones, an inverted L-shaped member that is curved lengthwise, there being an aperture formed near one end of said member, which aperture is adapted to receive a part of a locking device and a finger projecting from said member adjacent to the aperture therein.

7. The combination with an automatic telephone and its rotary dial plate, of an inverted L-shaped member adapted to overlie a portion of the top and edge of the dial plate of the telephone and said L-shaped member being provided with an aperture that is adapted to coincide with one of the apertures in the dial plate and to receive a part of a locking device.

In testimony whereof I affix my signature.

LEWIS F. MORTIMER.
